Richardson Company, Middletown, Ohio, a cor-
poration of Ohio

Application December 8, 1939, Serial No. 308,126

15 Claims. (Cl. 91—45)

This invention relates to the formation of fibrous tubes, containers, and the like. It relates more particularly to the application of sealing material to the internal surface of tubular bodies such as those adapted for the formation of containers. It is adapted for the application of a surfacing over all or over part of the interior surface of the tubular body after the formation thereof has been effected. It is likewise particularly adapted for use in conjunction with a machine for forming convolute tubes having an inner seam and to effect the application of a coating layer, either to the entire interior surface of the body, or in predetermined relation to only that part adjacent the seam, to thereby produce an effectively impervious interior surface within the tube.

It is accordingly a principal object of the invention to provide a simple and highly effective apparatus for treating the interior of tubes formed of fibrous material for the purpose of sealing the same and providing an impervious interior surfacing thereon.

It is a further object to provide such a device for receiving tubular bodies in predetermined indexed position and applying a sealing material to the interior surface thereof to thereby effect the application of an impervious surfacing thereon.

It is a still further object to provide such a device for receiving a series of convolute wound tubular bodies having inner seams in predetermined indexed position and for effecting the application of a band of sealing material to the inner seams to effectively cover over the same and to render such seams effectively impervious to the passage of the contents of the container.

Other objects and advantages will be apparent from the following description, the accompanying drawings, and the appended claims.

In the drawings—

Fig. 1 is a plan view of a device constructed in accordance with the present invention, certain parts being broken away to more clearly disclose the construction;

Fig. 2 is a view in side elevation of the same;

Fig. 3 is an end elevational view (on the line 3—3 of Fig. 2);

Fig. 4 is a partial plan view on a larger scale and with certain parts removed to more clearly disclose the construction and mode of operation;

Fig. 5 is a detail view showing the spray applying device;

Fig. 6 is a sectional view on the line 6—6 of Fig. 5; and

Fig. 7 is a detail view showing the arrangement for controlling the operation of the spray device in timed relation to the remainder of the mechanism.

5 While the device of the present invention may be operated separately and independently of the tube forming operation and with either convolute or involute wound tubes, it is particularly adapted for use in coordinated conjunction with a convolute tube forming machine which provides for the periodic delivery of one or a series of aligned tubes. For purposes of illustration the invention will be described in relation to the machine shown in the patent to Scusa et al. No. 2,163,318, 10 assigned to the same assignee as this application. As shown in such patent, the machine embodies a rotating mandrel assembly indicated partially and diagrammatically at 10 upon which the tubular bodies are convolutely formed, and 15 from which they are stripped at a predetermined point in the cycle of operation with the tubular bodies in definitely indexed position with regard to the location of the inner seam. The machine shown in such patent embodies, as a part of its 20 rotating mandrel assembly, means for effecting the application of a sealing material and treating the interior of the tubes as they are being stripped from the mandrels on which formation has taken place. Where however it is desired to 25 effect application of a sealing material to the interior of tubular bodies formed on mechanism which does not provide within itself for the application of such sealing material, or wherever it is desired to utilize a simple mechanism as a 30 separate device for effecting the application of sealing material, the present invention provides a simple and highly satisfactory arrangement for 35 so doing. Hence the present arrangement is applicable for use directly in conjunction with tube forming machines, or may be utilized separately 40 and for effecting the application of complete or partial coatings in predetermined position upon the interior of tubular bodies. In order to make clear the manner in which the device of the 45 present invention may be utilized with tube forming machinery, reference will be made throughout to the machine of the patent above referred to, it being understood however that the application of the present invention is not restricted to such particular machine.

The forming mandrel assembly 10 of the tube machine is so arranged that in one of its positions the formed tubular bodies may be stripped from the forming mandrel. While the machine referred to provides for forming a series of tubu-

lar bodies, it will be clear that the operation of the present invention is the same regardless of whether a single elongated tube is formed or whether it is cut into a series of tubes. This stripping is effected by means of a stripping device operated from the machine, and arranged to engage the rearmost body and to advance it forward and discharge it from the forming mandrel. The stripping device comprises a pair of sprocket chains 11 which carry body engaging members 12, one end of the sprocket chains being supported and rotatably driven within the tube forming machine, and the other end passing around sprocket wheels 13 which are mounted on shaft 14. The chains operate beneath a pair of guide rails 15, and preferably to one side thereof to facilitate the passage of the stripping device through the forming machine. This stripping operation takes place in timed relation to the cycle of operation of the forming machine such that a stripping operation occurs once during each cycle of operation. Likewise the arrangement is such that the tubular bodies are not rotated axially during the stripping operation, and being formed with their interior seams in alignment, such alignment continues throughout the stripping and other operations described herein. For convenience of operation the forming operations are so carried out that the seam is preferably located at the bottom of the tubular bodies in this stripping position.

The machine of the present invention is located adjacent the stripping device just described, and in such position that it receives the tubular bodies as they are being stripped from the forming machine. Where so located the stripping operation is preferably coordinated with its own operation as will be described more in detail. The machine comprises a structural framework 20 in which are mounted a pair of receiving members indicated generally at 21 and 22. As shown these members are mounted in side by side parallel relationship, each member being formed of relatively light-weight construction so that it may be conveniently supported in overhanging relation with a free unsupported end adapted to receive the tubular bodies exteriorly of the member and in telescoping relation thereto. This construction preferably comprises three external guide rods 24 spaced to approximate the internal dimensions of the tubular body to give proper and secure support thereto without however being sufficiently tight as to cause binding as the bodies move therover. A plurality of spacer members 25 locate a central tube 26 with respect to the guide rods, the tubular construction providing for high strength with minimum weight of material and inertia. An outer spacer 27 serves to receive and maintain the free ends of rods 24 in proper position.

The same construction is utilized for each of receiving members 21 and 22, these members being supported at their outer ends from a head structure 30 into which the guide rods 24 and tubes 26, respectively, are fastened so that the two receiving members are properly supported in spaced relation with respect to each other. The head 30 is pivotally supported by a main structural arm 31 and an outer reinforcing strap 32 which passes around the ends of the two receiving members and is welded to the head providing a firm and rigidly supported structure. The entire head assembly is mounted for oscillation and is carried upon a shaft 33 passing

through the hub portion 34 of the arm 31, and rotatably supported in a bearing socket 35 carried in the end frame member 36 of the framework 20.

5 The receiving members are arranged to be moved alternately into position in alignment with the end of the discharge track, and this is accomplished by imparting an intermittent oscillatory movement to the head and the receiving members. For this purpose shaft 33 is extended toward and adjacent the tube forming machine where drive means is provided for imparting such oscillatory movement in timed relation to the sequence of forming operations of 10 the machine, suitable bearing supports being provided for the shaft as required. In order to correlate the operation with that of the forming machine, connection is made to a drive shaft 40 which operates in predetermined timed relation 15 with respect to the operation of the forming machine, such as one rotation per cycle of operation. This shaft 40 carries a pinion 41 which meshes with a gear 42 having twice as many teeth so the gear will rotate at one-half the speed or one-half revolution per cycle of forming 20 operation. This gear carries a cam track 43. A follower 44 is carried by a crank arm 45 which is fastened to shaft 33, the contour of the cam track being so arranged that the shaft 33 is oscillated through one cycle of movement during 25 two cycles of operation of the forming machine.

Thus with receiving member 21 in alignment with the discharge track, a stripping operation 35 takes place to feed the tubular bodies upon such receiving member, following which the head is oscillated to bring receiving member 22 into alignment with the discharge track to receive the next discharge of tubular bodies, the two receiving members thus alternately receiving the 40 bodies as discharged from the forming device.

As each receiving member receives the supply 45 of tubular bodies thereon, the receiving assembly is tilted so that that member is thrown to the outside, and out of alignment with the discharge track. During the feeding of the subsequent supply of tubular bodies onto the alternate member, those tubes on the first such member are brought into discharging position with respect 50 to a pair of discharge chutes 51, and 52, respectively. Thus as shown, while the subsequent supply of tubular bodies is being forced onto receiving member 21, those on member 22 are in line with discharge chute 52. And means are 55 provided for effecting the discharge of such tubes into chute 52 comprising a discharge pusher 53. Such pusher is carried on a sprocket chain 54 which passes around sprocket wheel 55 at the forward end of the device, such sprocket wheel being carried by cross shaft 56 suitably supported from brackets 57. At the rearward end 60 sprocket wheel 58 is carried on shaft 59 which is suitably supported from the rear bracket member 36. A similar discharge pusher arrangement is provided upon the opposite side in position to engage the tubular bodies on receiving member 21 when such member is in the discharge position.

Shaft 56 is arranged to be driven at a proper speed by means of sprocket wheel 60 over which passes sprocket chain 61 suitably driven from sprocket wheel 62. The latter sprocket is preferably arranged to be driven from shaft 14 so that it will operate in definite timed relation 70 with respect to the remainder of the operations.

It will be clear from the above that with either receiving member in discharge position, it is located directly beneath and in line with the lower reach of sprocket chain 54, and in such position that the pusher member 53 will travel forwardly and into engagement with the end of the innermost body, to thereby cause the removal of the entire series of bodies thereon from the receiving member, the pusher being located upon the chain in predetermined relation such that it comes into engagement with such body just after the associated receiving member has been brought into alignment with its discharge chute.

The arrangement of the discharge chutes as to direction of discharge may be varied as desired, and hence only the initial portion of such chutes has been illustrated. If desired a feeder band 65 may be located in the lower portion of the chutes to frictionally engage the bodies and advance them forwardly through the chute. Such action is not essential however as the bodies will push each other through the chute as each successive discharging operation takes place. Such band may be suitably driven by means of a belt 66 and pulleys 67 arranged to be driven from shaft 14 in the direction to cause the feeding of the bodies in the discharge direction. Likewise it has been found desirable to provide one or more rollers 68 having an arcuate surface thereon which are positioned above the discharge chutes and so located as to engage the tops of the bodies as they are being discharged to prevent any tendency toward flattening thereof such as might occur with freshly formed tubes.

During a period of relative movement between the receiving members and the bodies received thereon and preferably during the removal of the bodies from the receiving members, means are provided for effecting the application of a sealing or surfacing material to the interior surface thereof. This may be effected in such manner as to cause the application of an overlying coating to substantially the entire interior surface; where however tubular bodies such as convolute bodies which have a protective surfacing thereon are to be treated, it is usually desired merely to effect the application of a relatively narrow band of sealing material to that portion adjacent the inner edge or seam, to thereby cover over said seam and prevent both seepage and wicking of the contents of the container into and through such edge material. For this purpose each tube 26 carries a forwardly extending light-weight bracket 70 adjacent the outer end of the receiving member, and to this bracket is pivotally supported a spray head 71, fastening means 72 providing for adjustably positioning the spray head at suitable spacing and in desired angular relationship with respect to the bodies within which it is received. Connection is made to the head for the supplying of fluid sealing material thereto by means of line 73, and air is supplied through line 74 under predetermined control to cause the atomizing of the spray material and the control of the application thereof, both lines extending back through tube 26 and out through head 30. The spray nozzle is indicated at 75 and may be suitably adjustable as to the size of the aperture, quantity of material delivered, width of spray, and so forth.

In order to effect application of the spray alternately from the two spray nozzles in predetermined timed relation to the cycle of operation, and throughout the longitudinal extent of the tubular bodies control means are provided

which are actuated from a suitable part of the mechanism. This is conveniently effected by means of a cam member located on a shaft which rotates once per cycle of operation. For this purpose shaft 40 is provided with a cam 76 which has a single rise thereon of a length such that it will provide for the desired duration of the spray during removal of the bodies from each of the receiving members. A pair of followers 77, 78 are arranged diametrically opposite each other so that they will be engaged sequentially in timed relation by the cam 76. Each follower is pivotally mounted upon a valve member 80 and spring pressed toward engagement with the cam. The valve chamber controls the supply of air from a source of air pressure which is connected at 81, the outlets being shown at 82 into which the air is thus alternately supplied under the control of the cam 76. Air outlets 82 communicate respectively with air lines 74 and thus first one receiving member and then the other is supplied with air under pressure, and there is thus produced a spray of the sealing material which occurs in timed relation so that the entire length of the tubular bodies is treated as the respective bodies are removed first from one receiving member, and then from another. As described above such sealing material may be applied either over the whole interior surface or over only a predetermined part thereof by suitable selection and arrangement of the spray equipment. The sealing material utilized may be any material such as desired for producing the desired proofing effect and for rendering the interior of the body resistant or impervious to the passage of moisture, other liquids, oil or grease, and the like, satisfactory results having been secured with the utilization of a cellulose ester material such as nitro-cellulose made up in solution with organic solvents.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. In a device for applying a surfacing material to the interior of a tubular body, a receiving member movable from a receiving to a discharge position and having a free overhanging end over which the body is received in the receiving position, means for alternately moving said receiving member from one of said positions to the other, means operable in the discharge position of said receiving member for removing the tubular body therefrom, and means carried by the receiving member for effecting the application of surfacing material to the interior surface of said tubular body as the same moves relative to said receiving member.
2. In a device for applying a surfacing material to the interior of a series of tubular bodies, a receiving member movable from a receiving to a discharge position and having a free overhanging end over which the series of tubular bodies is externally received in said receiving position, means for periodically moving said receiving member from one of said positions to the other, means operable in the discharge position of said member for removing the series of tubular bodies therefrom, and means coordinated with the movement of said series of tubular bodies over said receiving member for effecting the application of surfacing

material to the interior surface of each of said series of tubular bodies as they move relative thereto.

3. In a device for applying a surfacing material to the interior of a tubular body, a plurality of receiving members each movable from a receiving to a discharge position and having a free overhanging end over which the tubular bodies are received in receiving position, means for moving said receiving members successively into receiving and then into discharge positions, means operable when each of said members is in discharge position for removing the tubular body therefrom, and means carried by each of said receiving members for effecting the application of surfacing material to the interior surface of the tubular body during relative movement of said body with respect thereto.

4. In a device for applying a surfacing material to the interior of a series of tubular bodies, a plurality of receiving members each movable from a receiving to a discharge position and having a free overhanging end over which the series of bodies is externally received in receiving position, means for moving said receiving members successively into receiving and then into discharge positions, means operable when each of said receiving members is in the discharge position for removing the bodies therefrom and means coordinated with the movement of said tubular bodies over said receiving member for effecting the application of surfacing material to the interior surface of the series of bodies while on said member and as such bodies move relative thereto.

5. In a device for applying a surfacing material to the interior of a tubular body, a pair of receiving members movable alternately from a receiving to a discharge position and each having a free overhanging end over which the body is externally received in said receiving position, means for intermittently oscillating said pair of receiving members to move each of them alternately from one of said positions to the other, means operable in the discharge position of each of said members for removing the tubular body thereon, and means carried by each receiving member for effecting the application of surfacing material to the interior surface of the body during relative movement between the body and said means.

6. In a device for applying a surfacing material to the interior of a tubular body, a pair of receiving members having a common receiving position and individual discharge positions, each of said receiving members having a free overhanging end over which the body is externally received in said receiving position, means for intermittently oscillating said pair of receiving members to position each of them alternately in said receiving position with the other in its discharge position, means operable in the discharge position of each of said members for removing the tubular body thereon, and means carried by each receiving member for effecting the application of surfacing material to the interior surface of the body during relative movement between the body and said means.

7. In a device for applying a surfacing material to the interior seam of a convolute wound tubular body, a pair of receiving members movable alternately from a receiving to a discharge position and each having a free overhanging end over which the body is received in said receiving position with said seam in predetermined angular relationship, means for intermittently os-

cillating said receiving members to move each of them from the receiving position to the discharge position, means operable in the discharge position for removing the tubular body from said receiving member, and means carried by the receiving member in predetermined positioning thereon for effecting the application of a band of surfacing material in overlying relationship with respect to the inner seam of said tubular body during a period of relative movement between said means and said body.

8. A device of the character described adapted for effecting the application of an inner surfacing to a tubular body comprising a plurality of receiving members each having an overhanging end adapted in receiving position to receive formed tubular bodies exteriorly thereon, means for moving the receiving member with the tubular bodies thereon away from said receiving position and to a discharge position, means for thereafter removing the tubular bodies from said receiving member, means carried by the receiving member for effecting the application of surfacing material to the interior surface of the body as the body moves relative thereto, and means for coordinating the action of said removing means with the means for moving the receiving member so that the bodies are removed from each member during the time that a subsequent member is receiving an additional supply of tubular bodies.

9. A device of the character described adapted for use in the application of surfacing material to the inner surface of a tubular body comprising a pair of receiving members, means for supporting said members from one end in parallel overhanging relation, said members having a common receiving position for receiving tubular bodies in external encircling relation thereon and having individual discharge positions, means for moving said supporting means intermittently to alternately position each one of said members in said receiving position and the other in its discharge position, means for engaging the bodies on the member in the discharge position to cause removal thereof from said member, and means carried by each of said members and operable during movement of said body relative to said member for effecting the application of a spray of surfacing material to the interior surface of said body.

10. A device of the character described adapted for use in the application of surfacing material to the inner surface of a series of tubular bodies comprising a pair of receiving members, means for supporting said members from one end in parallel overhanging relation, said members having a common receiving position for receiving tubular bodies in external encircling relation thereon and having individual discharge positions, means for moving said supporting means intermittently to alternately position each one of said members in said receiving position and the other in its discharge position, means for engaging the bodies on the member in the discharge position to cause removal thereof from said member, and means coordinated with the movement of said tubular bodies over each of said members and operable in a predetermined one of the alternate positions thereof for effecting the application of a spray of surfacing material to the interior surface of said bodies.

11. A device of the character described adapted for use in the application of surfacing material to the inner surface of a tubular body

comprising a pair of receiving members, means for supporting said members from one end in parallel overhanging relation, said members having a common receiving position for receiving tubular bodies in external encircling relation thereon and having individual discharge positions, means for moving said supporting means intermittently to alternately position each one of said members in said receiving position and the other in its discharge position, means located in each discharge position and adapted to engage the inner end of the body upon said member when said member moves into discharge position for removing the body from said member, and means carried by each of said members and operable during movement of said body relative to said member for effecting the application of a spray of surfacing material to the interior surface of said body.

12. A device of the character described adapted for use in the application of surfacing material to the inner surface of a tubular body comprising a pair of receiving members, means for supporting said members from one end in parallel overhanging relation, said members having a common receiving position for receiving tubular bodies in external encircling relation thereon and having individual discharge positions, means for moving said supporting means intermittently to alternately position each one of said members in said receiving position and the other in its discharge position, means for engaging the bodies on the member in the discharge position to cause removal thereof from said member, means carried by each of said members and operable during movement of said body relative to said member for effecting the application of a spray of surfacing material to the interior surface of said body, and means for controlling the operation of said spray device in timed relation to the movement of said receiving members to cause application of a spray to the entire longitudinal dimension of said bodies.

13. A device of the character described adapted for use in the application of surfacing material to the inner surface of a series of tubular bodies comprising a pair of receiving members, means for supporting said members from one end in parallel overhanging relation, said members having a common receiving position for receiving tubular bodies in external encircling relation thereon and having individual discharge positions, means for moving said supporting means intermittently to alternately position each one of said members in said receiving position and the other in its discharge position, means for engaging the bodies on the member in the discharge position to cause removal thereof from

said member, means carried by each of said members and operable during movement of said bodies relative to said member for effecting the application of a spray of surfacing material to the interior surface thereof and a discharge conveyor for receiving the tubular bodies as they are removed from said member in the discharge position to withdraw the same therefrom.

14. A device of the character described adapted for use in the application of surfacing material to the inner surface of series of tubular bodies comprising a pair of receiving members, means for supporting said members from one end in parallel overhanging relation, said members having a common receiving position for receiving tubular bodies in external encircling relation thereon and having individual discharge positions, means for moving said supporting means intermittently to alternately position each one of said members in said receiving position and the other in its discharge position, means for engaging the bodies on the member in the discharge position to cause removal thereof from said member, means carried by each of said members and operable during movement of said bodies relative to said member for effecting the application of a spray of surfacing material to the interior surface thereof, and means for engaging the bodies during withdrawal at portions thereof spaced from the zone of contact of said removing means therewith to prevent buckling thereof.

15. A device of the character described for periodically receiving and effecting the application of a sealing material to the interior surface of a tubular body comprising a plurality of receiving members each having a free overhanging end and movable from a receiving position to a discharge position, means for intermittently moving said receiving members into said receiving position to receive the tubular body on said overhanging end and for thereafter moving said member with the tubular body thereon into discharge position, means for operating said moving means in predetermined timed relation to the periodic receiving of the tubular bodies, means operable in the discharge position of said receiving members to remove the tubular body therefrom in preparation for a subsequent receiving operation, and means operable during relative movement of said tubular body with respect to said receiving member for effecting application of a treating material to the interior surface of the body adapted to render the same substantially impervious.
